UNITED STATES PATENT OFFICE.

ABEL T. ATHERTON, OF LOWELL, MASS., ASSIGNOR TO THE WHITEHEAD
& ATHERTON MACHINE COMPANY, OF SAME PLACE.

CONDENSER FOR ROVING-MACHINES.

SPECIFICATION forming part of Letters Patent No. 261,294, dated July 18, 1882.

Application filed April 25, 1882. (No model.)

To all whom it may concern:

Be it known that I, ABEL T. ATHERTON, of Lowell, Massachusetts, have invented certain new and useful Improvements in Condensers for Roving-Machines, of which the following is a specification.

My invention has special reference to the production of a condenser-tube of the kind represented in Kelley's patent, No. 250,043, dated November 22, 1881—that is to say, a condenser-tube provided with a spiral bore of substantially cylindrical cross-section. The condenser represented in said patent consists of an exterior iron or steel tube, into which is tightly driven a brass core preliminarily provided with a spiral bore by means of a bore-cutting tool working through a peripheral slot extending lengthwise of the core. The condenser-tube made in this manner is defective and will not perform its work well. It is almost impossible to make the brass core to exactly fill the iron tube, while in any event there will remain at the periphery of the core the metallic edges bounding the slot, and the result is that fibers of cotton from the sliver passing through the condenser catch and gather on these rough portions of the bore to such an extent as finally to cause the sliver—or roving—to soon break down. This defect I propose to remedy as follows: I form and drill out, as before, the casting for the external tube. (Lettered C in said Kelley patent). I then place centrally within the tube an iron cylindrical core, which is bent into the form of a spiral having the pitch and size required for the spiral bore of the condenser, and of a less diameter than the internal diameter of the tube. I then pour into the tube molten "type metal" or other suitable composition metal, which fills the tube and completely surrounds the spiral core. As soon as the type metal has properly set the iron core is removed, and by this operation a smooth spiral channel or bore substantially cylindri-

cal in cross-section is left in the condenser-tube. If desired, I can cast the type metal or other suitable composition metal core (answering to the brass core of the Kelley patented condenser) separately from the external iron tube, employing in this casting operation the spiral iron core, as above provided, in order to obtain a type-metal core with a spiral bore, and then insert this cast core into the external tube. The result in either case is that I obtain a condenser composed of an outer tube filled with a tubular spirally-bored core whose inner surface is smooth and unbroken at all points from end to end. Such a condenser is represented in the accompanying drawings, in which—

Figure 1 is a longitudinal central section of the condenser with the spirally-bored core in elevation. Fig. 2 is a transverse section, and Fig. 3 is an end elevation of the same.

C is the external iron or steel tube, provided with nozzle C', flanged rear end, C², and worm-gear d', as in the said patented condenser.

The spirally-bored metallic core is represented at d.

In Fig. 2 the condenser is represented as mounted in a stand similar to that shown and described in said Patent No. 250,043.

What I claim as new and of my invention is—

The hereinbefore-described condenser, consisting of the external tube, in combination with the inner tube cast with a spiral bore of substantially cylindrical cross-section, and with smooth unbroken walls throughout, as herein shown and described.

In testimony whereof I have hereunto set my hand this 3d day of April, 1882.

ABEL T. ATHERTON.
